CLAIM

The ornamental design for a water purification device, as shown and described.

DESCRIPTION

FIG. 1 is a top, front perspective view of the water purification device according to a first embodiment;

FIG. 2 is a front view of the water purification device of FIG. 1;

FIG. 3 is a first side view of the water purification device of FIG. 1;

FIG. 4 is a rear view of the water purification device of FIG. 1;

FIG. 5 is a second side view of the water purification device of FIG. 1;

FIG. 6 is a top view of the water purification device of FIG. 1;

FIG. 7 is a bottom view of the water purification device of FIG. 1;

FIG. 8 is a top, rear perspective view of the water purification device of FIG. 1;

FIG. 9 is a top, front perspective view of the water purification device according to a second embodiment;

FIG. 10 is a front view of the water purification device of FIG. 9;

FIG. 11 is a first side view of the water purification device of FIG. 9;

FIG. 12 is a rear view of the water purification device of FIG. 9;

FIG. 13 is a second side view of the water purification device of FIG. 9;

FIG. 14 is a top view of the water purification device of FIG. 9;

FIG. 15 is a bottom view of the water purification device of FIG. 9; and,

FIG. 16 is a top, rear perspective view of the water purification device of FIG. 9.

The broken line showing of portions of the water purification device is included for the purpose of illustrating and forms no part of the claimed design.
